DESIGN FOR A BATHTUB

William D. Kraemer, Maywood, Calif.

Application June 20, 1938, Serial No. 77,949

Term of patent 14 years

To all whom it may concern:

Be it known that I, William D. Kraemer, a citizen of the United States, residing in Maywood, in the county of Los Angeles and State of California, have invented a new, original, and ornamental Design for a Bathtub, of which the following is a specification, reference being had to the accompanying drawing, forming part thereof.

I claim:

The ornamental design for a bathtub, substantially as shown.

WILLIAM D. KRAEMER.
